PIANO BENCH MUSIC CABINET

William H. Gelbaugh, Tacoma, Wash.

Application August 19, 1937, Serial No. 159,888

2 Claims.

(Cl. 45—64)

This invention relates to cabinets for holding music and has for its objects, first, to provide such a cabinet within the space under a piano-bench; second, in which the music may be sorted as to size of the sheets, the type of music, or in any other way desirable, and in which such sorted music is contained in separate compartments; third, in which the music holder is hidden when the piano-bench is in use; fourth, in which the music holder is tilted to bring the music in position for convenient handling when the bench lid is raised; fifth, in which a suitable stop on the music holder engages the bench frame to prevent the holder from being tilted beyond the dead center; and sixth, which is simple and cheap to make, efficient in use, and easy to operate.

I attain these and other objects by the devices, mechanisms, and arrangements illustrated in the accompanying drawing, in which—

Fig. 1 is a front elevation of my improved piano-bench music cabinet, showing the lid raised and illustrating the accessibility of the music in the several music compartments therein; Fig. 2 is a cross-section on the line 2—2 in Fig. 3, the lid thereof being closed; Fig. 3 is a cross-section of one end thereof; and Fig. 4 is a view similar to Fig. 2, with the bench lid raised and all the music compartments in position for the receipt of music.

Similar numerals of reference refer to similar parts throughout the several views.

The keeping of sheet music in a convenient place and in an orderly manner is generally recognized by musicians to be highly desirable and my improved music cabinet accomplishes both of these objects by placing the music in suitable compartments under the piano-bench, and by swinging the several compartments, when the bench lid is raised, into a suitably tilted or inclined position with all the compartments readily accessible so that any desired sheet of music may be withdrawn therefrom, and so that all the music sheets may each be placed and kept in its proper compartment.

Referring now to the drawing, it will be seen that the piano-bench comprises a four-sided frame composed of a rear panel 1, two end or side panels 2, and a front panel 3, all suitably secured together and supported on four legs 4, and this frame is provided with a lid 5 suitably secured to the rear panel 1 of the frame by means of hinges 6. The under side of the lid 5 is provided with two music compartments 7 formed by a sheet 8 supported by side and center strips 9 and a bottom strip 10. This structure there-

fore provides two pockets adapted to receive and hold sheet music, or music books.

The frame has no bottom closure but a music holder 11 is swung therein as illustrated in the drawing. This holder 11 comprises a structure having a base sheet 12 of slightly smaller dimensions than the inside of the said frame, and on which the holder 11 is erected, two side and two intermediate strips 13 and a bottom strip 14, all said parts 13 and 14 being mounted on the base sheet 12 and separating the three sheets 15 into three tiers of compartments 16 each adapted to receive sheet music. The holder 11 thus formed, therefore, is provided with a series of nine open compartments, each adapted to receive a plurality of pieces of sheet music, thus providing, in conjunction with the above-described compartments 7 on the under side of the lid 5, a total, as illustrated of eleven compartments and thus providing ample means to segregate the several kinds or types of music or opportunity to arrange the music sheets according to title, if so desired.

It will be observed that the end or side panels 2 of the frame are each provided with an additional inside strip 17, forming a shoulder 18 on its lower edge and provided with a suitably positioned trunnion bearing or hole 19. It will also be observed that the two ends of the swinging music holder 11 are each provided with a suitably positioned plate 20 rigidly secured thereto and that each of these plates is provided with a trunnion or pivot 21 extending laterally therefrom and entering said holes 19 in the frame. These trunnions 21 are in coaxial alinement. Also, it will be seen that the said plates 20 are provided with outward extending stop lugs 22 which are so positioned as to engage the under side of the said shoulder 18 on the frame before the holder is swung to its most elevated position, as hereinafter described. It will also be observed from the drawing that the position of the axis of the pivot holes 19 in the frame, is approximately central in the frame but is slightly nearer the rearward or hinged side thereof; and that the same axis lies close to the top sheet 15 of the music holder and in a correspondingly close position relative to the rearward or open end thereof, thus throwing the music holder 11 off balance on its pivots and causing it to tend to assume its inclined or open position (Fig. 4).

The base sheet plate 12 of the holder 11 is provided at each of its two rear corners with brackets 23 extending upward therefrom, to which a pair of connecting bars or links 24 are pivotally attached. The other ends of these links

24 are similarly attached to short brackets 25 which are secured to the under side of the lid 5. The position of the brackets 25 and the length of the link 24 are such that the holder 11 lies horizontal in the frame when the lid 5 is closed (Fig. 2) and so that when the lid 5 is raised beyond its vertical or dead center the stop lugs 22 engage the shoulders 18 of the frame to prevent the unbalanced holder from further rotation on the axis of its trunnions 21 and the joint between the bracket 23 and the link 24 is below the "dead center" of the mechanism, as shown (Fig. 4), and so that the lid 5 is opened or raised beyond its dead center; thus the apparatus automatically 15 stays open for the handling of the music in the several compartments, without the need of any latch or prop and under the combined gravitational forces acting on the lid 5 and on the unbalanced music holder 11, both of which tend 20 to resist the closing of the said lid. Thus it will be seen that the lid is moved through more than a right-angle while the music holder is moved thereby through a much smaller angle.

It is to be understood that variations in the 25 details of construction of my improved piano-bench music cabinet may be made without departing from the spirit of my invention as outlined in the appended claims, and that the words and terms used in the above specification and in 30 the claims are chosen for convenience and are intended to have as generic a meaning as the state of the art will permit.

Having, therefore, described my invention, what I claim and desire to secure by Letters Patent, is:

1. In a music cabinet, the combination of a supporting frame; a lid hingedly secured to said frame; a music holder pivotally mounted in said frame the longitudinal axis of said pivots being positioned adjacent the top edge of said music holder whereby, the said music holder, while substantially filling the lower portion of the space 10 contained by said frame, is unbalanced therein and tends to swing on its pivots from its horizontal position to its inclined position; and a long link connecting the upper portion of said lid to the rearward end of said music holder whereby, 15 when the lid is closed the music holder is in a horizontal position in the frame with its open rearward end lying adjacent the hinge of said lid and when the lid is raised the music holder is tipped into a rearwardly inclined position in said 20 frame.

2. A music cabinet as set forth in claim 1, together with a stop on said music holder adapted to engage the frame and to prevent the music holder from rotating to its dead center, and 25 wherein said link is of such length and position as to cause the lid to open beyond its dead center when said stop is in such frame-engaging position, whereby through the cooperation of the unbalanced weight of the music holder and the unbalanced position of the lid, said lid is held open.

W. H. GELBAUGH.
